UNITED STATES PATENT OFFICE.

JULIUS FERDINAND ADAMS, OF PITTSBURGH, PENNSYLVANIA.

DESIGN FOR A GAS HEATER.

Application filed November 9, 1923. Serial No. 7,724. Term of patent 3½ years.

To all whom it may concern:

Be it known that I, JULIUS FERDINAND ADAMS, a citizen of the United States, residing at Pittsburgh, in the county of Allegheny and State of Pennsylvania, have invented a new, original, and ornamental Design for Gas Heaters, of which the following is a specification, reference being had to the accompanying drawing, forming part thereof.

The figure is a front view of a gas heater, showing my new design.

I claim:—

The ornamental design for a gas heater as shown.

JULIUS FERDINAND ADAMS.
